BEER KEG COOLER

Herbert J. Zeller, Dundee, Ill., assignor to Motorola, Inc.,
Franklin Park, Ill., a corporation of Illinois

Filed Sept. 26, 1966, Ser. No. 4,010

Term of patent 14 years

(Cl. D67—3)

FIG.1

FIG.2

FIG. 3

FIG. 1 is a perspective view taken from front, left side and top of a beer keg cooler showing my new design;

FIG. 2 is another perspective view taken from the rear, right side and top thereof; and

FIG. 3 is a perspective view taken from the front, left side and top of a modified form of the beer keg cooler shown in FIG. 1, the rear and right side being the same as those shown in FIG. 2.

Since it is evident that the bottom of the claimed cooler is not seen during its normal use, the descriptive paragraph making this statement is deemed to be unnecessary and has been deleted from the specification. In the interest of clarity, the "illustrative purposes" paragraph has been amended to read as follows:

The broken line illustration of the dispensing portion of a beer keg in FIG. 3 is for purposes of illustration only.

I claim:

The ornamental design for a beer keg cooler, as shown and described.
